[57] CLAIM

The ornamental design for an electric cord securement, as shown and described.

DESCRIPTION

FIG. 1 is a perspective view of the design; FIG. 2 is an end elevation with the opposite end being a mirror image; FIG. 3 is a bottom plan view; FIG. 4 is an upper plan view; FIG. 5 is a side elevation with the opposite side being a mirror image; FIG. 6 is a perspective view of the second embodiment thereof; and, FIG. 7 is a perspective view of the third embodiment thereof. The undisclosed bottom plan views of the second and third embodiments are the same in appearance as the bottom plan view shown as FIG. 3. The fragmented cross-hatched shading shown on FIG. 3 is understood to cover the entire surface.
